UNITED STATES PATENT OFFICE.

JULIUS MATTSON, OF CHICAGO, ILLINOIS.

SPINDLE-TIGHTENER.

1,401,270.

Specification of Letters Patent. Patented Dec. 27, 1921.

Application filed March 16, 1921. Serial No. 452,726.

To all whom it may concern:

Be it known that I, JULIUS MATTSON, a citizen of the United States, and a resident of Chicago, in the county of Cook and State of Illinois, have invented a new and useful Improvement in Spindle-Tighteners, of which the following is a full, clear, and exact description.

My invention relates to improvements in devices for tightening spindles and more particularly to devices for holding driven spindles in milling machines, or the like, against longitudinal movement, and it consists in the combinations, constructions and arrangements herein described and claimed.

An object of my invention is to provide a device having means for engaging with a spindle to adjust the latter relative to its bearings and to prevent longitudinal movement of the spindle without interfering with the functional movements thereof.

A further object of my invention is to provide a device of the character described that is self-adjusting in that it has means for preventing play between relatively moving parts on account of wear on such parts.

A further object of my invention is to provide a device of the character described that is simple in construction and operation, not likely to get out of order easily, and thoroughly practical commercially.

A further object of my invention is to provide a device of the character described that can be applied to milling machines and the like of ordinary construction without extensive changes in the usual construction being necessary.

Other objects and advantages will appear in the following specification, and the novel features of the invention will be particularly pointed out in the appended claims.

My invention is illustrated in the accompanying drawings, forming part of this application, in which—

Figure 1 is a longitudinal section through a portion of a milling machine to which the device is applied,

Fig. 2 is a section along the line 2—2 of Fig. 1,

Fig. 3 is a section along the line 3—3 of Fig. 1, and,

Fig. 4 is an end view of a portion of the device, a portion thereof being broken away.

Referring now to the drawings, 1 denotes

a milling machine bed supporting a frame 55 having integral spaced apart parallel upright arms 3 and 4. The arm 3 is formed with an opening 5 having disposed therein a bushing 6 in which is rotatably mounted the enlarged portion 7 of a hollow shaft or 60 spindle 8. The latter is arranged with its remote end portion disposed in a bushing 9 secured in an opening 10 in the arm 4 and with its adjacent end portion extending beyond the corresponding end of the bushing 6 and threaded at 11 for engagement with a cutter 12. It is to be observed that the opening 10 and the opening 5 have their centers alined so that the shaft 8 is horizontally disposed. The ends of the bushing 70 9 extend beyond the corresponding sides of the frame 4 and the inner end of the bushing 6 likewise extends beyond the corresponding side of the arm 3.

A collar 13 is mounted on the shaft 8 75 and rigidly secured thereto at a spaced distance from the adjacent or inner end of the bushing 6 by pins 14, or the like. The peripheral wall of the collar 13 is threaded and screwed thereon in an outer collar 15 80 that is split as shown best in Fig. 2 and is positioned with respect to the axis of the shaft 8 to engage the bushing 6 at its inner end. The shaft 8 is formed with diametrically opposed longitudinally extending slots 85 16—16 through its walls in the portion thereof adjacent to the inner end of the bushing 9 and in these guide slots work pins 17—17 having their outer ends fast in a collar 18 and their inner ends fast in a hollow shaft 19 that is disposed in the bore 20 of the main hollow shaft or spindle 8 and is concentric therewith. The collar 18 is positioned to contact with the adjacent or inner end of the bushing 9 and its movement along the spindle 8 toward the arm 3 is limited by a collar 21 mounted on the spindle 8 and secured thereto by pins 22, or the like, so that a portion thereof extends slightly beyond the adjacent ends of the slots 100 16—16.

The auxiliary shaft 19, which is in effect a thrust rod, as will be hereinafter pointed out, projects beyond the adjacent end of the spindle 8 and has slidably mounted 105 thereon a disk 23 that has a diameter equal to that of the spindle 8, or possibly slightly less, and is arranged to abut the end of the

spindle. The shaft 19 is threaded exteriorly at 24 and has screwed thereon an adjusting disk 25 that is split radially as shown in Fig. 4. A compression spring 26 is disposed on the shaft 19 so that the ends thereof react against the disk 23 and the adjusting disk 25, respectively.

From the foregoing description of the various parts of the device, the operation thereof may be readily understood. The split collar 15 is turned on the inner collar 13 and as the former contacts with the bearing 6, it is obvious that the spindle 8 will be moved longitudinally until the collar 18 at the other end of the spindle has been contacted by the fixed collar 21 and moved against the bushing 9. The spindle 8 will thus be "tightened" so that the cutter 12 will be in position to engage work 27 without frictionally contacting the frame 3 or the bushing 6. When the spindle 8 has been moved into determined or adjusted position so that it is held against longitudinal movement, the collar 15 is locked in adjusted position relative to the inner collar 13. This is preferably accomplished by means of an expansion screw or bolt comprising an exteriorly threaded headed tubular member 28 split from its end longitudinally, as at 29, and screwed into registering threaded openings 30 and 31 extending through the end portions of the split collar 15 at right angles to the ends thereof, thereby drawing the ends together to lock the collar to the inner collar 13. A tapering screw 32 is screwed into the split end portion of the tubular member 28 that is threaded interiorly for the reception thereof to expand the split portion of the tubular member and thus lock the latter in its adjusted position.

When the spindle 8 has been secured in adjusted position in the manner described, the means for preventing play between the spindle and the hereinbefore described members that prevent longitudinal movement thereof is adjusted. This is effected by screwing the adjusting disk 25 on the shaft 19 to a desired position, thereby increasing the tension on the spring 26 and forcing the disk 23 firmly against the end of the spindle 8. The adjusting disk 25 is then locked in adjusted position by an expansion screw or bolt that is identical in essential respects with the expansion screw or bolt that has been described as locking the collar 15 in adjusted position. The parts of the expansion screw engaging the threaded openings 33 and 34 through the end portions of the split disk 25 have therefore been indicated by the same reference numerals as the like parts in the hereinbefore described expansion screw. It is obvious that the reaction of the spring 26 against the disk 23 and the adjusting disk 25 will thrust the spindle 8 in the direction of the arm 3, there-

by maintaining the collar 15 against the bushing 6 and at the same time will thrust the adjusting disk 25 in the opposite direction, thereby maintaining the collar 18 against the bushing 9, thus preventing play 70 between the collars 15 and the bushing 6 and between the collar 18 and the bushing 9 on account of wear on these parts, and thereby holding the spindle 8 against longitudinal movement without interfering 75 with the free functional movement thereof.

I claim:

1. The combination with a hollow driven spindle supported for rotation in separated bearings of a collar rigidly mounted on the spindle adjacent to one of said bearings and having its peripheral wall threaded, a slideable collar disposed on the spindle adjacent to the other bearing of the spindle, diametrically opposed guide pins having their outer ends fast in the inner wall of the slideable collar and having their inner ends projecting through guide slots through the walls of the spindle adjacent to its second named bearing, a collar rigidly mounted on the spindle at a determined distance from the second named bearing to limit the movement of the slideable collar in the direction of the first named bearing, an adjusting collar screwing on the first named collar 95 and operable to contact with the first named bearing to occasion a movement of the spindle in the direction of the second named bearing, whereby the slideable collar will be held against the second named bearing and 100 said spindle will be held against longitudinal movement relative to its bearings, and means connecting with the guide pins and exerting a thrust against the end of the spindle adjacent to the second named bearing for preventing play between said adjusting collar 105 and the first named bearing and between said slideable collar and the second named bearing on account of wear on the parts.

2. The combination with a hollow driven 110 spindle slidably and rotatably supported adjacent to its ends in separated bearings of means for adjusting initially the position of the spindle with respect to its bearings and for preventing movement of said spindle 115 toward one of said bearings, a slideable collar disposed on the spindle adjacent to its other bearing, a guide pin secured to the slideable collar and projected through a guide slot in the wall of the spindle, means for 120 limiting the movement of the slideable collar toward the first named bearing, and means connecting with the guide pin and exerting a thrust against the end of the spindle adjacent to the second named bearing for preventing play between the adjusting means 125 and the first named bearing and between the collar and the second named bearing on account of wear on the parts.

3. The combination with a slideably and 130

5 rotatably supported hollow spindle having a guide slot through its walls adjacent to its support, or a slidable collar disposed on the spindle, a guide pin secured to said collar and arranged to project into the inner bore of the spindle, means connecting with the guide pin and engaging the spindle at one

end for exerting a thrust against the spindle in one direction and for pulling the guide pin the opposite direction, and other means 10 for limiting the movement of the spindle in the first named direction.

JULIUS MATTSON.
